HAND FEED MECHANISM FOR FASTENER
SETTING MACHINESOtto J. Huelster, Waterbury, Conn., assignor to
Scovill Manufacturing Company, Waterbury,
Conn., a corporation of Connecticut

Application June 12, 1942, Serial No. 446,837

3 Claims. (Cl. 218—5)

My present invention relates to hand feed mechanism for fastener setting machines and more particularly to such machines which are foot operable by a treadle or the like.

Foot operable fastener setting machines as heretofore made and in extensive use at present are of two types (1) wherein the fastener elements are automatically fed to the respective dies in synchronously timed relation upon each operation of the treadle and (2) wherein the fastener elements are hand fed to the dies. The automatic machines are costly, are not necessary for certain types of work and require considerable time for repair or adjustment should anything go wrong with the feed mechanism. The hand feed machines, as heretofore made and used, have a relatively low efficiency and have the definite drawback of requiring the operator's fingers to be placed in the path of the setting punch or die, thus, constituting a hazard in the operation of such machines.

According to my present invention, I provide for use on fastener setting machines of a hand feed mechanism which is so constituted that the operator's hands need not be brought into the path of the setting punch, thus constituting a definite safety feature. I further provide in such machines novel delivery feeds for the fastener elements to the dies whereby the feed of the elements is greatly facilitated and the production of the machine is enhanced.

The invention will be better understood from the detailed description which follows when considered in connection with the accompanying drawing wherein I have shown certain preferred embodiments and wherein—

Fig. 1 is a perspective view of the upper portion of a fastener setting machine embodying my invention.

Fig. 2 is a fractional front elevation of the upper die and die-block of the machine shown in Fig. 1.

Fig. 3 is a section taken substantially along the plane of the line 3—3 of Fig. 2.

Fig. 4 is a section taken substantially along the plane of the line 4—4 of Fig. 2.

Fig. 5 is a section taken substantially along the plane of the line 5—5 of Fig. 2.

Fig. 6 is a top plan view of the lower die, die-block and delivery feed shown in Fig. 1.

Fig. 7 is a section taken along the plane of the line 7—7 of Fig. 6, and

Fig. 8 is a section taken substantially along the plane of the line 8—8 of Fig. 7.

In Fig. 1 of the drawing there is shown a fas-

tener setting machine having a plunger 10 which is slidable in a bearing 11 and adapted for reciprocation therein by a rocker arm 12 in a well-known manner. The lower end of the plunger 10 is recessed as shown at 13 and has secured therein an upper die 14 by means of a set screw 15, a portion of the bearing 11 being cut away as at 16 to provide a clearance for such set screw. The lower end of the die 14 is formed with a recess 17 of a form which is complementary to the fastener element, upon which the die is intended to act coincident with the fastener setting operation.

Carried by and movable axially of the die 14 is a hollow die-block 18, said parts being connected by means of a longitudinal slot 19 in the die and a pin 20 extending therethrough and anchored in the die-block. Pivotedly mounted upon pins 21 in recessed walls at opposite sides of the die-block are a pair of jaws 22 which are normally urged inwardly toward each other by coil springs 23, the inward movement of said jaws being limited by flattened ends on stop pins 24 as best shown in Fig. 5. The jaws 22 are adapted to support a fastener element when received within the die-block and to "give" or move outwardly upon being subjected to force by the fastener element when the latter is moved through the die-block by the die 14.

To facilitate the introduction or the feeding of a fastener element to the die-block 18, I have formed therein an inclined delivery feed or chute 25 extending upwardly and outwardly from above the jaws 22 through one wall of the block. Preferably, the wall of the die-block through which the feed or chute 25 extends is formed with a lateral projection 26 and it is through the intersection of the top and outer end of said lateral projection that the feed or chute 25 extends. In forming the die-block with a lateral projection and chute as above described, I have provided both visual and manual means for facilitating the introduction of the fastener element into the die-block since the senses of sight and/or touch, may be utilized, and in view of the inclination of the chute, gravity operates upon the fastener element when introduced into the die-block to guide and position said element upon the jaws.

Mounted on the table of the machine in axial alignment with the upper die 14 is a lower die or anvil 27, the upper face of which is of a form complementary to the fastener element upon which the die is intended to act after said element has been set by the die and slidably mounted on the lower die 27 is a die-block unit

28 which is normally urged upwardly upon the die by a coil spring 29, one end of which bears against a shoulder 28a on the die-block and the other end of which rests against a washer 30 supported on a sleeve 31 fixedly secured to the die or in any other manner. The die-block unit 28 is provided with a pair of spring actuated jaws 32 of a character quite analogous to the jaws 22 above described and mounted in the die-block in substantially the same manner as the jaws 22. The guided and slidable mounting of the die-block 28 upon the die 27 is also provided in a manner similar to that of the die block 18, namely through the provision of a pin 33 secured in the die-block and extending through a slot 34 in the die.

The die-block unit 28 includes a lateral projection 35 having formed therein a longitudinally extending recess 36 and mounted on the projection 35 to constitute a part thereof is a cover plate 37 which provides a longitudinal recess 38 of flattened cross-section extending substantially the full length of the projection, that is, from the interior of the die-block to the outer end of the projection. Mounted in the recess 38 for slideable movement therein is a pusher member 38a the function for which will presently appear. The top of the cover plate 37 is formed with a circular opening 39 which leads into the recess 38 and is adapted to provide for the introduction of a fastener element to said recess. To facilitate the introduction of such fastener element into said opening 39, the upper surface of the plate 37 surrounding part of said opening is curved, bent or tapered downwardly as shown at 40. The inner end of the pusher rod 38a is formed with a substantially semi-circular recess adapted to engage the base of a fastener element when introduced into the recess 38 and said inner end of the pusher rod is normally held within the recess 38 at a point outwardly of the opening 39 so as to permit the entering fastener element to seat on the base of the recess 38 in advance of the pusher rod. The pusher rod is normally urged and held in this outward position by an expansion coil spring 41 mounted within the recess 36 and encircling a pin 42 extending below and parallel to the pusher rod 38a and carried by a head or button 43 to which the pusher rod is also affixed. The outward movement of the pusher rod, however, is limited by the engagement of a stud 44 mounted in the upper face thereof with an abutment 45 on the cover plate 37. It will thus be seen that when a fastener element is introduced through the opening 39 onto the base of the recess 38, it will be engaged by the inner end of the pusher rod 38a as the latter is moved inwardly or toward the die-block to feed such fastener element to the die 27 in the die-block 28.

It will be noted that the feed or chute 25 which is intended to receive one of the fastener elements and the feed recesses 39 and 38 which are intended to receive a cooperating fastener element are disposed on opposite sides of the die-blocks with respect to the front of the machine. By virtue of this arrangement, an operator is thus enabled to feed one of the fastener elements with the left hand and the other of the fastener elements with the right hand.

In the operation of the machine, an operator, usually a woman, will pick up one fastener element with her left hand from a left-hand supply source which she will insert into the upper delivery feed, and with her right hand will pick

up the complementary or cooperating fastener element from a right-hand supply source and drop it into the lower delivery feed, and with one of the fingers of said right hand she will engage the button 43 and move the pusher inwardly so as to position the fastener element on the lower die. When this is accomplished, the article or material to which the fastener elements are to be attached is positioned between the dies and the treadle operated to bring the dies into setting relation to set or attach the fastener elements to the article or material. It will thus be appreciated that the feeding of fastener elements with the aid of the present invention is not only greatly facilitated, because the operator does not have to hunt around to find the receiving opening in the die-blocks for the respective parts of the fastener elements, but also provides a definite and decided safety feature for the machine since the operator's fingers are not brought into the line of movement of the setting dies.

Although any kind of trays or receptacles for holding the fastener elements may be used and may be disposed in close proximity to the respective feed means, I have found that by mounting trays of a special character in a manner as shown in Fig. 1 that the feeding of the fastener elements is still further facilitated. These trays are identified by the reference numerals 46 and 47 and are each adjustably mounted to a part of the machine. The tray 46 is uncovered and formed with an open guide trough 48, the end of which is disposed in juxtaposition to the outer end of the chute 25 in the upper die and the tray 47 is also uncovered and formed with an open guide trough 49, the end of which is disposed in overlying relation to the cover plate 37 in juxtaposition to the opening 39 therein leading into the recess or delivery feed 38. From the disposition and character of the trays 46 and 47, it will be at once apparent that instead of an operator being obliged to physically pick up and introduce the fastener elements into the respective delivery feeds, the engagement of an element upon the trays by a single finger of the operator and the imparting of a sliding movement to the element will suffice to accomplish this transfer.

From the foregoing detailed description, it will thus be apparent that I have provided a simple and novel means for expediting the hand feeding of fastener elements to a fastener setting machine and have accomplished this in a way which also eliminates the hazard of injury to the operator's fingers in the carrying out of such operations.

The device, as disclosed, although considered by me to be a preferred embodiment of my invention, it is to be understood that I do not wish to be limited to the precise details of construction as disclosed since these may be varied within the range of engineering skill without departing from the spirit of the invention.

What I claim is:

1. A fastener setting machine comprising a setting die, a die-block carried by and movable relatively to said die, said die-block having spring actuated jaws for supporting a fastener element and having an inclined guide chute extending upwardly and outwardly from above the jaws through one side of the block for receiving and delivering by gravity to the jaws a fastener element when inserted into said chute, and an uncovered tray disposed laterally of the die-block

and having an open guide trough the end of which is in juxtaposition to the outer end of the guide chute in the die-block when the latter is in normal relation to the die, said tray having a substantially smooth horizontally disposed base for holding fastener elements and providing a surface over which the fastener elements may be manually fed by a sliding movement into the inclined guide chute.

2. A fastener setting machine comprising a die, a die-block carried by and movable relatively to said die, a delivery feed through which a fastener element can be fed to the die-block, and an uncovered tray disposed laterally of the delivery feed and having an open guide trough the end of which is in juxtaposition to the fastener receiving opening in the delivery feed when the latter is in normal relation to the die, said tray having a substantially smooth horizontally disposed base for holding fastener elements and providing a surface over which the fastener elements may be manually fed by a sliding movement into the delivery feed.

5 3. A fastener setting machine comprising an upper die and a lower die, each die having a die-block which is carried by and movable relatively to the die and formed with a delivery feed through which a fastener element can be manually fed to the die-block, the delivery feeds on the respective die-blocks being disposed on opposite sides thereof with respect to the front of the machine, and uncovered trays disposed respectively laterally of the delivery feeds in the die-blocks, each tray having an open guide trough the end of which is in juxtaposition to the fastener receiving opening in a delivery feed when the latter is in normal relation to its respective die, said trays each having a substantially smooth horizontally disposed base for holding fastener elements and providing a surface over which the fastener elements may be manually fed by a sliding movement into the respective delivery feeds.
